Attorney

UNITED STATES PATENT OFFICE.

JOHN J. VETTER, OF INDIANAPOLIS, INDIANA.

DAVENPORT.

968,097.

Specification of Letters Patent. Patented Aug. 23, 1910.

Application filed May 2, 1910. Serial No. 558,791.

To all whom it may concern:

Be it known that I, JOHN J. VETTER, a citizen of the United States, residing at Indianapolis, county of Marion, and State 5 of Indiana, have invented certain new and useful Improvements in Davenports, of which the following is a specification.

My invention relates to davenports, and particularly to folding davenports wherein 10 the back and seat may be arranged to form a bed or couch.

More specifically my invention relates to the means for connecting the pad, usually the portion forming the back, to the base 15 or box of the device.

In davenports of the character under consideration a two part pad is provided one part of which forms the seat and the other part the back of the device. The seat portion is slidably mounted upon the base, which is usually of box form, and the back portion is hingedly connected thereto, so that the seat may be slid forwardly and the back dropped to horizontal position, together 20 forming a mattress when the device is to be used as a couch or bed. To prevent separation of the pad from the base, the back portion of the pad and the base are connected by an arm pivotally connected at its ends 25 to brackets secured to said back and base respectively. Heretofore this has been a substantially permanent connection and the pad can only be removed from the base after having removed the screws which hold 30 the bracket to the pad. Consequently in shipping or handling the davenports they must be packed into a single crate or bundle, which on account of its bulk and weight is difficult to handle and expensive to move or 35 ship, or, one of the brackets must be removed from its respective parts and when the device is again set up it must be re-attached thereto. When the latter expedient is resorted to, the screw holes soon become, 40 after several moves, so worn that the screws will not securely hold the brackets in place.

The object of my invention is to provide improved means for attaching the pad to the base whereby the pad may be readily and 45 quickly removed when desired and as readily secured in place.

Other objects will appear hereinafter.

My invention consists generally in a davenport provided with the connecting arm and brackets as above mentioned equipped with a detachable connection between said

arm and one of the brackets whereby said arm and bracket may be readily disconnected when desired and as readily secured together.

My invention further consists in various 60 details of construction and arrangements of parts all as will be fully described herein-after and particularly pointed out in the claims.

My invention will be more readily understood by reference to the accompanying drawings forming a part of this specification and in which—

Figure 1 is an end view of a davenport embodying my invention in its preferred 70 form, the end or arm being removed and illustrating in dotted lines the pad extended to form a mattress when the device is to be used as a bed, Fig. 2 is a detail elevation of the end of the back forming pad, Fig. 3 is 75 an elevation upon an enlarged scale of the connecting arm and brackets, and illustrating a modified manner of securing the arm to the bracket pin, and Fig. 4 is a section on the line $\alpha-\alpha$ of Fig. 3. 80

Referring now to the drawings 1 indicates the base or box, 2 an end arm thereof, 85 and 3 and 4 the seat portion and back portion respectively of the pad. The seat portion 3 is preferably hingedly connected to 90 the back portion 4 as at 5, the fabric covering of the pad forming the hinge.

The seat 3 is slidably mounted on the base 1 in order that the same may be drawn forward when it is desired to use the device 95 as a bed, and the back portion 4 swings down behind the same and into a plane therewith as shown in dotted lines in Fig. 1.

A bracket 6 is secured by screws 7 to the base 1 and a similar bracket 8 is secured to the back portion 4 by screws 9. An arm 10 pivotally connected at its ends to the brackets 6 and 8 respectively normally prevents separation of the pads 3 and 4 from the base. The portions of the device so far described are similar to those in general use and no claim is made to the same. As now constructed the pivotal connections between the arm 10 and the brackets are permanent and it is therefore necessary, in order to remove the pad from the base, to remove the screws 9, and I have found that after the screws 9 have been removed and replaced a number of times the screw holes in the portion 4 become so worn as to prevent the 110 bracket 8 from being securely fastened to the back.

In carrying out my invention I provide a detachable connection between one of the brackets 6 and 8, preferably the latter, whereby said arm and bracket may be readily separated when desired and as readily secured together. The permanent pivotal connection between the opposite bracket and the arm 10 may be retained, and in practice I prefer such construction.

10 11 indicates a rivet extending through the bracket 6 and the respective end of the arm 10, forming the permanent pivotal connection.

15 Extending outwardly from the face of the bracket 8 is a pin 12 upon which the adjacent end of the arm 10 is pivotally mounted, said end being provided with an aperture 13 to receive said pin, and a pin 14 extends transversely through the end of the 20 pin 12 to normally hold the end of the arm on said pin. The pin 14 may be the end of a rod 15 slidably mounted on the end of the pad 4 as shown in Figs. 1 and 2 or it may be a cotter pin 14' as shown in Figs. 3 and 4. 25 The former construction affords ease of manipulation and when such is employed the rod 15 is slidably mounted in eyes or guides 16 close against the ends of the pad 4 and is off-set as shown to form the pin 14 30 to extend through the aperture in the pin 12.

It is obvious that with this construction the connection between the arm 10 and bracket 8 is as strong and as durable as the permanent connection heretofore provided, 35 and that by removing the pin 14 the arm 10 may be detached from the bracket 8 and hence from the pad, permitting the pad to be removed from the base, and that the parts may be as readily secured together. In taking 40 the davenport apart or assembling the

same, it is not necessary to remove any screws, or to use any tools, and further the device may be taken apart and put together as frequently as desired without weakening any of the parts. It is to be understood 45 that the arm and brackets are to be arranged upon each end of the device.

Having described my invention what I claim as new and desire to secure by Letters Patent is:—

1. In a davenport, a base, a seat and a back, in combination with a bracket secured to said base, an arm pivotally connected at one end to said bracket, a second bracket secured to said back, a pin projecting from 55 said second bracket, one end of said arm being perforated to receive said pin, and a pin extending through the outer end of the first said pin to retain said arm on said pin, substantially as described.

2. In a davenport, a base, a seat and a back, in combination with a bracket secured to said base, an arm pivotally connected at one end to said bracket, a second bracket secured to said back, a pin projecting from 65 said second bracket, one end of said arm being perforated to receive said pin, and a rod slidably mounted on the end of said back, the end of said rod forming a pin to extend through the outer end of the first 70 said pin to retain said arm on said pin, substantially as described.

In testimony whereof I have signed my name to this specification in the presence of two subscribing witnesses.

JOHN J. VETTER.
